SHOEMAKING

Fred L. Ayers, Watertown, Mass., assignor, by
mesne assignments, to United Shoe Machinery
Corporation, Paterson, N. J., a corporation of
Massachusetts

Application November 9, 1932, Serial No. 641,850

6 Claims. (CL. 36—22)

This invention relates to the art of shoe-making and more particularly to that field of shoe-making wherein an insole is used as the part to which the marginal portion of the shoe upper is attached while on the last. Thus, in making so-called cement-process shoes and in making McKay, welt, and other shoes, it is the practice to attach the marginal portion of the shoe upper to the insole. In order to realize satisfactory attachment of the shoe upper to the insole, it is necessary to use an insole of substantial thickness, even though such qualities as flexibility and light weight, frequently desired in the fore part of the shoe, have to be sacrificed.

In accordance with the present invention, the marginal portion of the shoe upper is attached as ordinarily to the insole, but, after such attachment has been effected, the insole is reduced in thickness at the fore part of the shoe beginning preferably substantially at the front shank line and terminating substantially at the tip, thereby conducing to a shoe which is lighter and more flexible at its fore part. While such reduction in thickness may be performed in connection with insoles of various types, including leather insoles, as by gouging out a layer of insole material of the desired thickness, nevertheless, the principles of the present invention are applicable to especial advantage in connection with plied insoles, that is, insoles made up of two or more plies or laminations and whose plies may be readily separated at their planes of bonding or plying. In such case, the insole may be prepared for the shoe-making process in such a way that one or more of the outer plies may be quickly lifted or removed from the fore part after the marginal portion of the shoe upper has been suitably fastened to the insole as ordinarily.

I may cite the application of my invention to a cement-process shoe which is made by initially channeling the edge of the insole inwardly to form two laps, one of which is turned upwardly and serves as a lip to which the edge portion of the upper is attached as by staples, and the other lap of which serves to receive the marginal portion of the upper in cemented relation thereto. In making such shoes, the lip simply serves as a temporary means for holding the upper in place while the cement employed for bonding the marginal portion of the upper to the insole is setting or hardening. In other words, the lip, together with the staples or other fastening means and excess upper, is cut or trimmed away after anchorage of the upper to the insole by the cement has been effected. In such case, when the

insole is made up of two plies, it is a comparatively easy matter to remove the outer ply material at the forepart of the shoe, as all that need be done is to form a kerf in the insole at the front shank line, say, about one-quarter inch in front of the ball line, extending from one edge of the insole to the other and of a depth terminating at the plane of plying. The fact is that when the channel is formed substantially at the plane of plying or somewhat inwardly of the plane of plying, the removal of the temporary lip, staples and excess upper, as hereinbefore described, leaves the outer ply material free for easy removal through the formation of a kerf such as described, as such a kerf develops a starting edge which can be grasped by the operator so as to allow a pulling away or removal of the outer ply material from the rest of the insole. It is thus seen that the insole may be prepared in such a way as to permit a prompt reduction of the thickness of the insole at the fore part of the shoe immediately after the upper has been attached to the insole. In the case of McKay or welt shoes, wherein the marginal portion of the upper is tacked or sewed to the insole, the insole may be pre-scored to permit the desired removal of the outer ply material at the fore part of the shoe immediately after the upper has been fixed to the insole.

With the foregoing and other features and objects in view, my invention will now be described in conjunction with the accompanying drawings, wherein,—

Figure 1 represents in plan view an insole prepared in accordance with my invention for making one type of cement shoe.

Figure 2 is a plan view of the shoe bottom immediately after the temporary lip, staples, and the excess upper have been cut away, the removable outer-ply portion of the insole being partly lifted away from the insole adjacent to the shank line.

Figures 3, 4 and 5 represent sections on the line 3—3 of Figure 2 at different stages of the shoe-making process.

Figure 6 is a side view of the finished shoe, the fore part being shown in section.

Figures 7 and 8 are fragmentary sections through a shoe containing a somewhat modified form of insole at different stages of shoe-making.

Figure 9 is a plan view of an insole pre-scored for use in a McKay shoe.

Figure 10 is a plan view of such a shoe bottom immediately after the upper has been tacked to the insole, the removable outer ply portion of

the insole being partially lifted from the rest of the insole adjacent to the shank line.

Figure 11 represents a section on the line 11-11 of Figure 10, with the outer sole secured in place.

5 Figure 12 is a plan view of a welt shoe bottom immediately before the removable outer ply portion has been removed.

10 Figure 13 represents a fragmentary section through the fore part of the completed welt shoe.

10 Referring now in detail to the drawings, the inner sole shown in Figure 1 may comprise two plies of substantially equal thickness, namely, an outer ply of comparatively stiff material, and an inner ply of comparatively soft and flexible material. The stiff outer ply lends itself nicely to channeling and may be channeled from its edges inwardly, excepting at its heel portion immediately adjacent to the plane of plying, thereby forming a pair of laps. As shown in Figure 1, a 15 kerf x may be formed across the outer ply at the front shank line. This kerf may extend from one side edge of the insole to the opposite edge and be of a depth terminating at the plane of plying. The outer lap 10 formed by the channel is, as 20 shown in Figure 3, bent outwardly to form a lip to which the edge portion of the shoe upper 11 is secured as by staples 12 while held on a last 13. This securement is merely a temporary one designed to hold the shoe upper in place, for the 25 marginal portion 14 of the upper and/or the inner lap 15 receives a coating of liquid cement designed to set or harden and thereby firmly anchor the shoe upper. After the cement has set, the lip 10, staples 12, and the edge portion of the 30 upper, are removed by cutting down as far as the outer surface of the marginal portion 14 of the upper, as shown in Figure 4. This leaves the upper ply material beginning with the kerf x and terminating with the tip line y , as shown in Figure 2, free for removal. The operator may, therefore, grasp the starting edge z developed by the kerf and pull the upper ply material away from the rest of the insole, as illustrated in Figure 2. When this has been accomplished, a cavity or 35 recess is formed at the shoe bottom between the edges of the shoe upper and this cavity may, as shown in Figure 6, be filled with a filling material 16 preferably of a soft and flexible nature before the outer sole 17 is cemented as ordinarily to the 40 shoe bottom. The removal of the outer ply material of the insole at the forepart of the shoe greatly enhances the flexibility of the shoe where flexibility is highly desired. The shank and heel portions of the shoe are, however, preserved rigid, 45 as rigidity is a desirable quality at these portions. It might be mentioned that the insole is preferably completely prepared before it is tacked to the last. In other words, the kerf x is preferably formed therein and the lip 10 is turned outwardly before tacking to the last is effected. The 50 kerf x permits the insole to break or flex easily and assume the contour of the shank portion of the last and it also facilitates the outward turning of the lip 10 at the shank portion of the insole without crowding or bunching at this portion.

When the insole is made up of two plies, either of which is sufficiently stiff to permit successful channeling, channeling may be effected in the inner ply on a plane sufficiently removed from the plane of plying to dispense with the need of shoe filler material after outer ply material has been removed from the fore part of the shoe. Thus, as shown in Figure 7, the inner ply material 18 70 may be somewhat thicker than the outer ply ma-

terial 19 and channeling may be effected in the inner ply 18 on a plane sufficiently removed from the plane of plying so that when the marginal portion 20 of the shoe upper is bonded to the inner lap 21, the outer face of the marginal portion 5 will lie substantially flush with the plane of plying. This means that when the temporary lip, staples, and the edge portion of the shoe upper are removed and the removable fore part of the outer ply is torn away from the rest of the 10 insole, a substantially flat bottom requiring no filling material will result, as shown in Figure 8.

In preparing a two-ply insole for the manufacture of McKay shoes, it is desirable to pre-score the insole as illustrated in Figure 9. The 15 scoring is done inwardly of the edge portion of the insole to leave an edge zone of sufficient width to permit tacking of the marginal portion of the shoe upper to the insole. The scoring may start substantially at the front shank line of the insole and take the general contour of the insole, as shown in Figure 9, with the score line reaching internally to the plane of plying. After the marginal portion of the shoe upper 21 has been secured by tacks 22 to the insole, the operator 25 may remove the outer ply material defined by the line of score, as shown in Figure 10. In this case too, a cavity is left in the shoe bottom where the outer ply material has been removed, and this cavity may be filled with a soft, flexible filling 30 material 22, as shown in Figure 11, before the outer sole 23 is stitched as ordinarily to the inner sole.

In making welt shoes, an inner sole composed of two plies may be prepared as ordinarily with 35 a stitch-receiving channel 24 inwardly of its edges and a properly rounded edge portion 25. Immediately beyond the stitch-receiving channel 24, the insole may be pre-scored in the same way as is an insole designed for use in McKay shoes. 40 After the insole has been assembled with the shoe upper and welt, the removable outer ply portion 26 may be torn away and the cavity thereby formed may be filled with a suitable filling composition 27, as shown in Figure 13, before the 45 outer sole 28 is stitched to the welt 29 as ordinarily.

It is thus seen from the foregoing description of various applications of my invention, that I am enabled to start out with an insole of sufficient 50 thickness, say, the usual four-iron insole, perform the necessary shoe-making operations as ordinarily, and then to remove that portion of the insole which is unnecessary and which detracts from the desired qualities of lightness and 55 flexibility at the fore part of the shoe, whereas the rest of the shoe, including the shank and heel portions, is preserved rigid, as is usually desired. While the principles of my invention have been described specifically in connection with 60 such types of shoes as McKay or Littleway, welt, and a particular form of cement-process shoe, it is to be understood that these applications of my invention are merely illustrative and that other specific embodiments of my invention are possible 65 and indeed highly practicable. For instance, in channeling the insole for cement-process shoes, it is possible to cut the channel outwardly from inside the edges of the insole, instead of from the edges inwardly, as previously described, to 70 form a temporary lip for the attachment of the shoe upper; the lip, excess upper, and staples being subsequently removed or trimmed away. This sort of channeling allows the outer ply to be readily removed at the fore part of the insole, 75

but the marginal or edge portion of the insole is left intact with both plies. The intact marginal or edge portion does not, however, detract unduly from the flexibility afforded by the zone which 5 has been reduced in thickness and which exists throughout the fore part of the insole, excepting at such intact marginal or edge portion.

I claim:—

1. An insole channeled from its edges inwardly to form lapping edge portions, one of said portions being bent outwardly to form a lip, said insole having a kerf substantially at the front shank line and extending from its outer face to its 10 interior.

15 2. An insole channeled from its edges inwardly to form lapping edge portions, one of said portions being bent outwardly to form a lip, said insole having a kerf substantially at the front shank line and of a depth commencing at its outer face 20 and terminating substantially on the plane of channelling.

25 3. An insole made up of at least two plies channeled substantially on the plane of plying inwardly from its edges to form lapping edge portions, one of said portions being bent outwardly to form a lip, said insole having a kerf substan-

tially at the front shank line and of a depth commencing at its outer face and terminating substantially on the plane of channelling.

4. An insole made up of at least two plies, one being relatively flexible and the other relatively stiff, said stiff ply being channeled inwardly from its edges adjacent to the plane of plying to form lapping edge portions, one of said portions being bent outwardly to form a lip, and said insole having a kerf substantially at the front shank line 10 and of a depth beginning with the outer face of said stiff ply and terminating substantially on the plane of plying. 5

5. An insole made up of at least two plies, one of said plies being scored inwardly of its edges 15 substantially to the plane of plying along a line following the contour of the fore part and including a kerf substantially at the front shank line.

6. An insole made up of at least two plies, one of said plies being scored inwardly of its edges 20 substantially to the plane of plying along a line following the contour of the fore part and including a kerf substantially at the front shank line and whose ends terminate within the insole edges.

FRED L. AYERS. 25
